UNITED STATES PATENT OFFICE.

EDWARD S. HARTMAN, OF ALLEGHENY, PENNSYLVANIA.

MACHINE FOR SHARPENING THE EDGES OF PLOWSHARES AND OTHER PLOW-STEELS.

SPECIFICATION forming part of Letters Patent No. 268,401, dated December 5, 1882.

Application filed June 5, 1882. (No model.)

To all whom it may concern:

Be it known that I, EDWARD S. HARTMAN, of Allegheny, in the county of Allegheny and State of Pennsylvania, have invented a new and useful Improvement in Beveling-Machines; and I do hereby declare the following to be a full, clear, and exact description thereof.

It has heretofore been customary to sharpen or bevel plowshares and the cutting-edges of other agricultural steels and various cutting-tools under a trip or drop hammer upon a bed-die the face of which and the face of the hammer converged toward each other. The blank was presented by the operator, who fed it along until by a series of blows the entire edge was beveled. In this operation the operator was guided entirely by the eye, and his experience in regulating the force of the blows of the hammer and the distance the blank should be placed under it. Consequently the quality of the work depended upon the skill of the workman, and was not uniform in character. Moreover, the operation was comparatively slow and the edges produced uneven.

To enable others skilled in the art to make and use my invention, I will now describe its construction and operation by reference to the accompanying drawings, in which—

Figure 1 is a side elevation of my improved beveling-machine. Fig. 2 is a plan view, and Fig. 3 is a side view of the moving jaw and lever.

Like letters of reference indicate like parts in each.

At the front end of a suitable frame, *a*, is the lower die-bed, *b*, upon which is secured a stationary die, *c*. In a jaw, *d*, is the upper or movable die, *e*. The faces of the two dies *c* and *e* converge toward each other, so that they form a flaring cavity, *f*, in which the edge of the blank is placed when it is presented to them. The jaw *d* is provided with journals *d'*, which have their bearings in suitable boxes, *g*, in the sides of frame *a*. Extending back of the journals is an arm or lever, *d''*, of the jaw *d*, which rests upon an eccentric, *h*, mounted on a power-shaft, *i*. This eccentric *h* operates the jaw *d*, and thereby the die *e*, through the medium of the lever *d''*. The jaw *d* is so journaled and adjusted with reference to the die *c*

that the die *e* has a curvilinear movement as it approaches the jaw *c*, and hence not only bevels the blank, but draws the metal slightly, so as to produce a longer sharper bevel than it would if struck a directly vertical blow by a drop or hammer. The shaft *i* is provided with a pulley, *k*, and fly-wheel *l*.

The operation of my machine is as follows: Power is applied to the pulley by a belt, and the jaw *d* is caused to oscillate with great rapidity. The plate or other blank is presented by thrusting the edge into the cavity *f*, and then feeding it along as the jaw nips, bites, or pinches an edge on it. The operation of the jaw is extremely rapid, and the plate can be moved along with almost no perceptible pause as the jaw bites.

No especial skill is required in using the machine, as it is only necessary in presenting the plate to rest it on the lower die and press it as far in as it will go. A uniform and perfect edge is produced.

By making the lower die flat the bevel will be made on one side only, the face of the upper die converging to that of the lower one. This is equally a part of the invention, and is useful in sharpening tools in which the bevel is on one side only.

A modification of my machine is to mount both dies in moving jaws, each of which may be operated by eccentrics on the same shaft.

The invention is useful for sharpening and beveling agricultural steels and tools of all kinds, and also for beveling metal for many other purposes.

What I claim as my invention, and desire to secure by Letters Patent, is—

In a machine for beveling plowshares and other implements, the combination of a bed or anvil die having a beveled face and a rocking die having a beveled face, the latter carried by a pivoted lever and arranged above the bed-die to coact therewith, substantially as and for the purpose specified.

In testimony whereof I have hereunto set my hand this 8th day of May, A. D. 1882.

EDWARD S. HARTMAN.
